[57] CLAIM

The ornamental design for a vaginal applicator, as shown and described.

DESCRIPTION

FIG. 1 is a perspective view of a vaginal applicator, showing our new design, with the plunger in withdrawn position;

FIG. 2 is a side elevational view thereof, with all other side elevational views being a mirror image thereof;

FIG. 3 is a side elevational view thereof with the plunger in depressed position;

FIG. 4 is a bottom plan view thereof; and

FIG. 5 is a top plan view thereof.

FIG. 1.

FIG. 2.

FIG. 3.

FIG. 4.

FIG. 5.
